By his Attorney,

F. L. Ewin.

UNITED STATES PATENT OFFICE.

EDWARD J. BROOKS, OF EAST ORANGE, NEW JERSEY, ASSIGNOR TO E. J. BROOKS & CO., OF NEW YORK, N. Y.

METALLIC TAG.

SPECIFICATION forming part of Letters Patent No. 278,214, dated May 22, 1883.

Application filed November 16, 1882. (No model.)

To all whom it may concern:

Be it known that I, EDWARD J. BROOKS, a citizen of the United States, residing at East Orange, in the State of New Jersey, have invented a new and useful Improvement in Tags or Labels, of which the following is a specification.

In my drawings and specifications forming part of Letters Patent No. 254,601, dated March 7, 1882, for "sealing-press," and No. 259,472, dated June 13, 1882, for "label-rack for freight-cars," I show and describe what are known as "car-cards" or "destination-cards," and means for attaching the same to the sides of railway freight-cars; as "labels" illustrative of the nearest approximations to the present invention heretofore known and used. Such cards or labels are made of paper or card-board and require secure and extended support, as they frequently become water-soaked *en route*; but even when secured within racks, and more particularly when tacked to the cars, as they are most commonly, the weather very often affects such cards, so that their inscriptions become washed off or completely obliterated before the cars reach their destinations. Moreover, such cards can be used but once, and their cost, including printing and handling, the wear and tear of cars, if they are tacked on, and that of their racks, if the latter are used, together with the first cost of such racks, make up a heavy item of expense to be covered by earnings of railway companies and freight-lines. The racks are also objectionable because they hide the lettering on the cards or deface them, so as to hinder or prevent readily reading them to a greater or less extent.

In the Hamilton patent, No. 167,525, dated September 7, 1875, now owned by E. J. BROOKS & Co., an ordinary paper shipping-tag used in connection with a metallic seal as a substitute for the larger car-card is shown. A tag of this description is as perishable and as costly, and limited to use once, and once only, as the paper car-card, and in order to preserve its shape it must be made so small that it is impossible or difficult to read its written transient matter by lantern-light after handling it to turn its face outward. An accidental or mischievous pull is sufficient to tear it off in an instant, and

its loss almost inevitably follows. Consequently, and owing to other practical objections, paper tags of this description are not used to any considerable extent as substitutes for car-cards.

55 My present invention consists in strong and durable water-proof tags or labels of a novel construction, as hereinafter set forth and claimed. The same have been designed, primarily, for use on railway freight-cars as substitutes for the perishable labeling cards and tags aforesaid, and to be suspended in the form of tags, so as to fully expose their faces, with freedom from liability to destruction, defacement, or loss in any of the aforesaid ways. 60

Figure 1 on the sheet of drawings which accompanies this specification is a face view of an unused water-proof tag or label in the form of a tag for freight-cars, illustrating this invention. Fig. 2 is another face view of the same 70 as used. Fig. 3 represents an exaggerated section on the line 3 3, Fig. 2. Fig. 4 is a face view of another species of the same genus of tags or labels; and Fig. 5 is another face view, showing another species of my said tags or labels with a "holder," as illustrative means for attaching the same. This holder forms no part of my present invention, but is hereby reserved for a future application for patent. 75

Like letters of reference indicate corresponding parts in the several figures.

I propose to make my water-proof tags or labels for railway freight-cars of various shapes and sizes, suited to the various requirements of different railway companies and freight-lines, 85 for marking cars carrying local freight as well as "through cars," and for showing the utmost that is shown on the large cards now in use and in like conspicuous characters, as well as the simpler marks which are sometimes employed. I have therefore shown three tags, or labels in the form of tags, A B C, of different sizes and shapes, and have selected the first, A, Figs. 1 to 3, as the smallest and most simple, to exhibit the features of novelty which are 90 common to all the forms. Water-proof tags or labels for use on railway freight-cars (and for analogous uses) should be, and it is the object of this invention to produce tags or labels which are, not only water-proof, or adapted for 100

exposure to wind and weather, but sufficiently rigid to keep their shape during repeated uses, strong enough to resist accidental and mischievous pulls, and adapted to be made of distinguishing colors for different uses, and to bear such transient marks as may be necessary, as well as the permanent "printed matter" commonly used for facilitating their preparation and manifesting genuineness, and to be freed from such transient marks for repeated use. To accomplish this object I make each tag or label as follows: I take suitable thin metal, preferably tin, (tin-plate,) for the "body" *z*, and provide one or both sides of the same, preferably both sides, with "enamel," *y*, of any desired color, said enamel being formed by painting the metal and baking or "burning in" the paint in a manner well known. Upon the face of the tag, or each face, if reversible tags be desired, I print with an ordinary printer's ink the required permanent matter in characters *x*, and burn the same in, so that it becomes incorporated with the enamel *y* and absolutely indelible. The body metal is enameled, and the enamel is printed, as above, "in the sheet," and the sheets of metal are subsequently stamped or cut and stamped into tags, or labels in the form of tags, for example, of suitable size and shape, as shown, for example, with perforations *w*, one or more, near the upper edge of each, by which to suspend the tag or label upon the side of a car, or to fasten the same in place, as illustrated by Fig. 5. A tag or label so finished and ready for use is illustrated by Fig. 1. The date, number of car, initials of consignee, description of contents, or any one or more of these which may be used, with, in some cases, the names of the shipping-places from which and to which the car goes, and the name of the sealer, or any such or other like "transient" or special marks, must be supplied as occasion demands. I have discovered that said enamel furnishes an excellent foundation for such marks, printed by means of a "rubber stamp," or written by means of a suitable pen of rubber, quill, or steel, or a suitable "pencil" of rubber, or stenciled (preferably the former) with a water-proof ink mixed with turpentine. This ink adheres with all requisite tenacity to said enamel, being absolutely water-proof, while it can be readily sponged off with turpentine without in any manner otherwise defacing or impairing the tag. Any suitable water-proof ink adapted to be so used may be employed, together with any suitable chemical for erasing the marks made therewith. I so print or write such transient matter in characters, *xx*, erasable by means of turpentine, for example, but not by water, and so provide for the repeated use of the tags or labels. This I propose to systematize as follows: On the arrival of each car at its destination its tag or label must be taken off by the opener of the car and returned to the office which is-

sued the tag or label as a kind of receipt, 65 showing that the car was duly received by the party or road to whom it was consigned. The tags or labels may be returned once a day, once a month, or once every six months, as required. When so received back at the office 70 which originally issued them they will be examined and noted, and then passed to a boy or girl, who, with a sponge dipped in turpentine, will quickly and easily remove all traces of the said transient matter, together with finger-marks and the like, from their faces, 75 restoring the tags or labels substantially to their original condition. They will then be ready to be used over again, and will be sent out to the proper stations for use. The tags or labels 80 may be so cleaned and reused from thirty to fifty or a hundred times at a trifling outlay for labor and materials, thus saving thousands of dollars annually to their users.

In printing the backs of reversible tags or 85 labels provision will be made for their use upon cars in returning them. On one side, for instance, will be "Milwaukee to Boston, via L. S. & M. S. Ry., by C. & H. R. R. & B. & A. R. R." and on the other side "Boston to Milwaukee, via B. & A. R. R., by C. & H. R. R. & L. S. & M. S. Ry." This would obviate returning the tags or labels in bulk.

I propose to use the construction of tags shown by the drawings accompanying this 95 specification, as above described, and substantially the aforesaid system of reuse, in providing a substitute for paper tags now used in connection with or as substitutes for baggage-checks, by railway passenger lines and express 100 companies, the permanent marks (*x*) and transient matter (*xx*) to be appropriate to particular uses of the tags, as in the illustrations, Figs. 1 to 5.

My car tags or labels above described may 105 be fastened or held by means of the car-door lock or seal in any approved way, or more loosely fastened, or otherwise attached in any preferred manner.

To attach tags or labels in the form of tags 110 of large size, I prefer to use a suitable holder, D, Fig. 5, represents such a holder employed to attach the said tag or label C. As I do not claim the holder herein, I omit any further description thereof.

I claim as new and desire to patent under 115 this specification—

An improved tag having a body of sheet metal provided with an impermeable enamel, and with permanent marks indelibly incorporated in said enamel, and having blank spaces adapted to receive water-proof transient marks upon said enamel, as herein specified, for the purposes set forth.

EDWARD J. BROOKS.
